UNITED STATES PATENT OFFICE.

HARRY B. CORNISH AND JOHN B. MOORE, OF BLUE EARTH CITY, MINN.

COFFEE-POT.

SPECIFICATION forming part of Letters Patent No. 361,489, dated April 19, 1887.

Application filed December 21, 1886. Serial No. 222,473. (No model.)

To all whom it may concern:

Be it known that we, HARRY BUTTON CORNISH and JOHN BENJAMIN MOORE, both of Blue Earth City, in the county of Faribault and State 5 of Minnesota, have invented a new and Improved Coffee-Pot, of which the following is a specification, reference being had to the annexed drawings, forming a part thereof, in which—

10 Figure 1 is a vertical transverse section of our improved coffee-pot, and Fig. 2 is a side elevation of the percolator.

Similar letters of reference indicate corresponding parts in both views.

15 The object of our invention is to provide a coffee-pot in which coffee may be made by the percolation of hot water through the ground coffee; also, to provide means whereby the cloth or other straining or filtering medium by which the ground coffee is supported 20 may be readily attached to and removed from the percolator.

Our invention consists in the construction and arrangement of parts, as will be herein-after fully described and claimed.

25 To the cylindrical portion *a* of the percolator *A* is secured the conical part *b*, which fits into the top of the ordinary coffee-pot, *B*, in the place of the usual cover. To the top of the cylindrical portion *a* is fitted a cover, *c*, and to the bottom of the conical part *b* are secured two downwardly-convex bars, *d*. To the smaller end of the conical portion *b* is fitted a ring, *e*, which is connected with one side of the conical 30 part *b* by a hinge-joint, *f*. In the opposite side of the conical part *b* is raised a ridge, *g*,

which is engaged by the wired upper edge of the ring *e* when the said ring is closed over the conical part *b*. A piece, *h*, of cloth or other suitable material, is placed over the basket formed of the bars *d* while the ring *e* is open, and is clamped in place on the lower end of the conical part *b* by closing the ring over it, as shown in Fig. 1.

40 Ground coffee is placed in the basket, where it is supported by the cloth *h*, and the coffee is extracted from it by pouring hot water through it, the extract being received in the coffee-pot *B*.

45 When the cloth *h* becomes clogged or otherwise unfit for use, it may be readily detached by removing the ring *e*.

Having thus fully described our invention, we claim as new and desire to secure by Letters Patent—

50 The combination, with the percolator *A*, having the cross-bars *d* at its lower end and the projection *g* on its outer surface near its lower end, of the ring *e*, wired around its upper edge and hinged to the percolator at a point 55 opposite the projection *g*, the wired upper edge of the ring being adapted to snap over and be held by said projection, whereby a cloth may be readily clamped between the ring and the lower end of the percolator, substantially as set forth.

HARRY B. CORNISH.
JOHN B. MOORE.
